UNITED STATES PATENT OFFICE.

NELSON T. SHARP, OF MEMPHIS, TENNESSEE.

SELF-SERVING STORE.

Application filed March 2, 1928. Serial No. 258,549.

The present invention relates to a self serving store, and aims to provide a novel and improved arrangement whereby the various fixtures are associated for providing a maximum amount of floor space, as well as for permitting the clerks at the checking counter to have an unobstructed view of the entire shopping area of the interior of the store.

10 With this principal object in view my invention contemplates the provision of shelving arranged near the front and side walls of the store with those at the sides extended forwardly at acute angles in double tiers and 15 a similar arrangement provided centrally at the rear end of the store room so that a clerk at the checking counter can easily see all of said shelves as a check on articles removed therefrom by purchasers, walkways 20 being provided in rear of the side shelving and between the centrally and angularly arranged shelving for permitting the replenishing of articles thereon from the rear thereof.

My invention further contemplates providing a checking counter adjacent the entrance and exit doorway of the store, a turnstile adjacent the checking counter permitting persons to pass therethrough without passing by the counter when entering 30 the store and requiring those desiring to leave the store to pass by the checking counter, the operation of said turnstiles being adapted to actuate a basket conveyor for returning baskets to a bin from which they 35 were taken by persons entering the store, the baskets being placed upon the conveyor by the clerk after he has checked the articles selected by the patron.

My invention provides a store arrangement of the above indicated character, which is of a simple nature, which may be installed economically, and one which will be efficient and practical in use.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein:

Figure 1 is a top plan showing my improved arrangement,

55 Figure 2 is a perspective view of the

checking counter and turnstiles, illustrating the manner in which persons enter and leave the store,

Figure 3 is a fragmentary side elevation 60 of a portion of the shelving, and

Figure 4 is a fragmentary vertical section taken on line 4—4 of Figure 3.

Referring to the drawings, the numeral 10 designates the front wall of a store having 65 windows 11 therein at opposite sides of a door opening 12, the latter providing the only way of entering and leaving the store. The opening 12 is closed by doors 13 hinged at opposite sides of the door frame. Spaced 70 slightly from the front wall 10 at each side of the door opening 12 are shelves 14 which extend toward the opposite side walls of the store and are connected to longitudinally arranged shelves 15 slightly spaced from the 75 opposite side walls of the store. By spacing the shelves 14 and 15 from the front and side walls of the store it can be seen that walkways are provided behind said shelves which will permit the replenishing of goods on the 80 shelves from the rear thereof. The shelves 15 extend rearwardly to points past the center of the store and are connected to shelves 16 extending forwardly at acute angles thereto. Spaced from the angularly arranged 85 shelves 16 and in parallel relation therewith are shelves 17, providing walkways 18 in the rear of said shelves for replenishing of goods on both the shelves 16 and 17. The ends of the walkways 18 at opposite sides of 90 the store are closed by walls 19 which may contain thereon lists and prices of the various goods arranged upon the various shelves.

In the rear of the store room adjacent the 95 side walls are arranged various fixtures, such as a delicatessen department 20, a fruit and vegetable department 21, a stand for brooms and mops 22, a self serving refrigerator 23, a meat market 24, and a cold storage meat 100 refrigerator for the meat market 25. Glass show cases 26 may be arranged at the forward portions of the delicatessen department and meat market in order to display goods therein. By the arrangement shown it can 105 be seen that people desiring to purchase goods at the various departments will have ample room and congested conditions will be obviated. The delicatessen department 20 and the meat department 24 are in communication with walkways 27 which extend along 110 the side walls of the store and communicate

with the walkways 18 leading to shelves 16-17 and walkways 28 in rear of the side shelves 15. In the rear of the store room proper is arranged a walkway 29 which communicates with the side walkways 27 in order that clerks assigned to placing goods on the shelves may easily pass around the store room in the rear of the shelves without being observed by purchasers in the shopping area 10 of the store. Arranged centrally of the shopping area and extending forwardly from the rear thereof is a pair of shelves 30 in spaced parallel relation so as to provide a walkway 31 therebetween which communicates with the rear walkway 29. The forward end of the walkway 31 is closed by a wall 32 which may contain reading matter relative to various goods displayed.

In the center of the shopping area of the 20 store, slightly in advance of the intermediate portion thereof and directly in rear of the entrance and exit opening 12, is a checking counter 33, of substantially U-shape in plan presenting side counters 34 and a rear end counter 35. The forward ends of the side counters 34 are closed by a railing 36 so as to provide a compartment or cage in which the checking clerks are stationed, and spaced from the forward ends of said counters are a pair of turnstiles 37 through 25 which patrons must pass when entering and leaving the shopping area of the store. Arcuate railings 38 connect with the ends of the side counters 34 and extending outwardly 30 therefrom conform to the path of movement of the bars 39 of the turnstiles, being supported from the floor by means of posts 40. On opposite sides of the turnstiles from where the arcuate railings 38 are placed are cases 41 which have the upper portions 35 thereof constructed, as at 42, for supporting bags or other receptacles to be used by patrons of the store. It can be seen that the arcuate cases 41 also conform to the path of movement of the bars 39 of the turnstiles 37 and form guards compelling 40 patrons to pass through the turnstiles when entering the shopping area of the store. Attached to the cases 41 are forwardly extending railings 43 attached to the front 45 wall 10 of the store, as indicated by the numeral 44. When a person enters the store and desires to proceed to the shopping area he must pass through either one of the turnstiles 37, as indicated by the arrows 45.

At the outer sides of the side counters 34 and spaced therefrom intermediate their ends are arcuate bins 46 which contain baskets that may be used by persons entering the 60 store and desiring to purchase goods. From the outer, forward portions of the bins 46 are railings 47 which extend forwardly to points forward of the outer ends of the arcuate railings 38 and then at an angle 65 towards the posts 48 of the turnstiles, as at

49. At the points where the railings 47 and 49 meet posts 50 are provided for supporting said railings, while the outer ends of the railings 49 are attached to the posts 48 to assist in supporting the same. Extending 70 rearwardly from the bins 46 at the inner sides thereof are railings 51 which terminate in line with the rear counter 35. As shown in Figures 1 and 2 of the drawings, a person after purchasing articles may leave the 75 store only by passing by the checking counter 33, as the means of entrance to the turnstile from the shopping area of the store is between the counter 33 and the railings 51, bins 46, and railings 47, as clearly illustrated by the arrows 52 shown in Figure 1 of the drawings. The turnstiles are of a construction for turning only in certain directions so that it is impossible for a person to enter or leave the store otherwise than 85 that desired by the operator of the store.

Attached to each turnstile 37 and extending upwardly therefrom is a rod 53 having on the upper end thereof a gear 54. The gears 54 at the upper ends of the two rods 90 mesh with other gears 55 at the forward ends of horizontal rods 56, supported by means of uprights 57 having bearings 58 theron through which the rods extend. The rear ends of the rods 56 extend through the outer 95 ends of frames 59 and carry thereon rollers 60 about which belt conveyors 61 are trained from rollers 62 carried at the inner ends of the frames. These frames are supported above the side counters 34 by means of uprights 63 supporting the inner ends thereof, while relatively wide guard boards 64 support the outer ends rising from the bins 46. By referring to Figures 1 and 2 of the drawings, it can be seen that the conveyors 100 105 are associated with the bins in a manner so that baskets carried by the conveyors will be deposited into the bins. As the inner ends of the conveyors extend to the side counters 34, baskets may be placed thereon by checking clerks after looking over goods selected by the purchaser. As the conveyors 61 are elevated, persons may conveniently pass thereunder when leaving the shopping area 110 of the store. By having the turnstile connected with the conveyors, it can be seen that the operation of the turnstiles will actuate the conveyors, thus forming an economical form of power. Also, by having the turnstiles operate the conveyors they will 115 120 be actuated according to the turning movement of the turnstiles and thus obviate the provision of any other operating means.

The detail construction of the shelves adjacent the side walls of the store, centrally of the store, and the shelves 16 and 17 disposed at an angle thereto, is shown in Figures 3 and 4 of the drawings, being constructed of a plurality of uprights 65 having horizontal boards 66 supported thereby on 125 130

which the articles to be displayed are placed. Below the lowermost boards or shelves 66 on the side towards the shopping area, are arranged facing boards 67 so that articles 5 placed on the floor beneath these shelves from the rear will not be visible by the parties making purchases, thereby providing storage compartments 68 in which goods may be placed that are to be exhibited for 10 sale on the shelves above thus obviating the necessity of a store room of enlarged size for containing the goods prior to the placing thereof on the shelves as well as making it more convenient to replenish the shelves. 15 Beneath the shelves 66 on which the articles are placed for sale are small belts 69, trained over bars 70 semi-spherical in cross section supported at the forward or purchasing side of the shelves and over rotatably mounted 20 rollers 71 at the rear side of said shelves. Between the bars 70 and rollers 71 are idlers 72 for holding the lower run of the belt up so that the same will not be visible or interfere with articles placed on the shelves there- 25 beneath. In front of the bars 70 are horizontal strips 73 which extend along the entire length of the shelves and have openings 74 therein so that the portions of the belts extending over said bars will be visible. An 30 opening 74 is arranged in the strip at each point where a belt is positioned. On the belt 69 are numerals 75 visible through the openings 74 to indicate the price of the articles arranged on the shelf below. By hav- 35 ing various prices printed on the belt it can be seen that turning the belt will bring different prices to view in order to compensate for any change in prices, as well as the placing of differently priced articles upon the shelves. 40 As the spaces between the shelves 66 are open from both sides, it can be seen that a clerk in the store may pass down the various walkways and replenish the shelves with articles, while the purchasers in the 45 shopping area on the opposite side of the shelves may select articles desired by them. In this way the clerks do not interfere with the parties making purchases and thereby relieve any congestion in the store which 50 might otherwise result.

When the store is open for business, checking clerks are stationed in the cage or compartment surrounded by the counter 33 and railing 36, and some of the clerks may be 55 assigned to placing articles upon the various shelves. When the meat market, delicatessen, and fruit and vegetable departments are used, clerks are employed in these departments in order to wait on customers. 60 Persons desiring to make purchases in the store, enter the main entrance and pass through either one of the turnstiles 37 in the direction indicated by the arrows 45. While passing through the turnstiles they 65 may remove paper bags from the racks 42 in the bins 41 and pass to the basket bins 46 where they may remove a basket if they desire to purchase a large quantity of goods. Then passing on to the different shelves, they may select articles desired. If they 70 desire meat, fruit, or vegetables, or goods at the delicatessen counter they are waited on by clerks stationed in these departments for that purpose. After they have made their purchases, they pass by the counter, in the 75 direction indicated by the arrows 52, passing between the bins 46 and the side counters 34 of the main counter 33. At the counters the articles are checked over and paid for by the purchasers, and the clerk then places 80 the empty baskets upon the conveyors 61, and when the articles are paid for and wrapped at the checking counters, the patrons pass again through the turnstiles at opposite sides of the counter and out through the 85 door opening 12. As the parties pass through the turnstiles turning the same the rotatable movement of the shafts is transmitted to the conveyors 61 in order to actuate the same and deposit the empty baskets 90 into the basket bins 46 where they may be again used by other patrons entering the store and desiring to make purchases. As articles are removed from the various shelves, the clerk assigned to placing articles on 95 the shelves may easily remove articles from the storage compartments 68 in replenishing articles on the shelves.

By the arrangement shown and described, it can be seen that possible congestion in the 100 shopping area is reduced to a minimum, and that by arranging some of the shelving in double tiers extending towards the checking counters it increases the article exhibiting and selling capacity of the store and the 105 clerks at the checking counters may at all times have a clear and unobstructed view of the entire shopping area of the store in order to detect anyone attempting to pilfer any article by secreting it instead of placing it 110 in the receptacle along with other articles purchased.

Having thus described my invention, what I claim as new is:

1. A self-serving store having an entrance 115 and exit doorway, a checking counter within the store adjacent said doorway, a pair of turnstiles adjacent said checking counter and slightly beyond each side thereof, basket bins, conveyors arranged for depositing 120 baskets placed on the same into said basket bins, and means for operating said conveyors upon operation of said turnstiles.
2. A self-serving store having an entrance 125 and exit doorway, a checking counter within the store adjacent said doorway, a turnstile adjacent said checking counter between the same and the entrance and exit doorway, railings arranged for compelling patrons to pass by the checking counter when 130

leaving the store and for permitting persons to enter the store without passing by the checking counter, a basket bin, a conveyor for receiving baskets and depositing the same into the bin, and means for actuating said conveyor upon operation of said turnstile.

3. A self-serving store having an entrance and exit opening therein, a substantially U-shaped checking counter having side counters 10 and a rear counter, basket bins spaced from the opposite side counters of said checking counter, a pair of turnstiles positioned between the side counters and entrance and exit doorway and slightly to the outer sides 15 of said side counters, and railings arranged for compelling patrons to pass between said basket bins and said counters when leaving the store and for permitting persons entering the store to obtain baskets from said bins 20 without passing by the checking counter, and conveyors arranged above said side counters for depositing baskets into said basket bins when placed thereon by clerks at the checking counter, and means for actuating said

conveyors upon operation of said turnstiles.

4. A self-serving store having an entrance and exit doorway, a checking counter within the store adjacent the doorway, a turnstile at one side of said checking counter, a bin to receive baskets used by the purchaser 30 in making purchases, an overhead conveyor leading to said bin and by which the baskets are returned, and means responsive to the operation of the turnstile for operating the conveyor.

5. A self-serving store having an entrance and exit doorway, a checking counter within the store adjacent the doorway, a turnstile at one side of said checking counter, a bin to receive baskets used by the purchaser, 40 an overhead endless belt trained over rollers and leading to the bin, a horizontal shaft connected to one of the rollers, and a vertical shaft extending from the turnstile and geared to said horizontal shaft for operation 45 of the conveyor by the operation of the turnstile.

NELSON T. SHARP.
